Filed Dec. 11, 1972, Ser. No. 314,254

Term of patent 14 years

Int. Cl. D24—99

U.S. Cl. D83—1 E

FIG. 1 is a side elevation of a caster support for wheel chairs or the like, showing my new design with portions of the tubular support being broken away to indicate indeterminate length;

FIG. 2 is a fragmentary side elevation as seen from the left of FIG. 1;

FIG. 3 is a fragmentary side elevation as seen from the right of FIG. 1;

FIG. 4 is a top plan view thereof; and

FIG. 5 is a bottom plan view thereof.

The broken lines are shown for illustrative purposes only.

The characteristic feature of my design resides in the specific configuration of the biased tubular juncture as best illustrated in FIGS. 1, 2 and 3 in the drawing.

I claim:

The ornamental design for a caster support for wheel chairs or the like, as shown and described.
